DESIGN FOR A COVER FOR AN INSTRUMENT CASING

Douglass A. Young, East Orange, N. J., assignor
to Westinghouse Electric & Manufacturing
Company, a corporation of Pennsylvania

Application November 29, 1939, Serial No. 88,544

Term of patent 14 years

To all whom it may concern:

Be it known that I, Douglass A Young, a citizen of the United States, residing at East Orange, in the county of Essex and State of New Jersey, have invented a new, original, and ornamental Design for a Cover for an Instrument Casing, of which the following is a specification, reference being had to the accompanying drawing, constituting a part thereof.

Figure 1 is a view in front elevation of a cover for an instrument casing embodying my invention; and

Fig. 2 is a view in side elevation of the cover illustrated in Fig. 1.

I claim:

The ornamental design for a cover for an instrument casing, substantially as shown.

DOUGLASS A. YOUNG.
